UNITED STATES PATENT OFFICE.

LINCOLN ISHAM, OF NEW YORK, N. Y.

BANJO-SNARE.

1,291,903.

Specification of Letters Patent.

Patented Jan. 21, 1919.

Application filed March 19, 1918. Serial No. 223,287.

To all whom it may concern:

Be it known that I, LINCOLN ISHAM, a citizen of the United States, residing at New York, in the county and State of New York, have invented certain new and useful Improvements in Banjo-Snares, of which the following is a full, clear, and exact specification.

This invention relates to snares especially 10 designed for use on banjos to give an effect when the banjo is played similar to that of a snare drum.

One object of the invention is to provide 15 a snare which may be quickly attached to any banjo or similar instrument and detached therefrom as occasion requires without altering the instrument in any way or marring its appearance. Another object is 20 to provide a detachable snare which is simple in construction and inexpensive to manufacture. Further objects will appear as the description proceeds.

The invention will be first hereinafter described in connection with the accompanying 25 drawings, which constitute part of this specification, and then more specifically defined in the claims at the end of the description.

In the accompanying drawings, wherein 30 similar reference characters are used to designate corresponding parts throughout the several views:

Figure 1 is a sectional view through one edge of the head of a banjo, showing the 35 snare in place thereon.

Fig. 2 is a detailed plan view of the snare.

Fig. 3 is an elevation thereof looking at the free ends of the snare cords.

Fig. 4 is a detailed perspective view of 40 the device with its parts separated, and Fig. 5 is a plan view of a banjo head showing more clearly how the snare may be attached thereto.

In Figs. 1 and 5 the head of a banjo is 45 illustrated at 1, the rim thereof at 2, the clamping ring at 3 and the snare as a whole at 4. The snare cords 5 are preferably made of silk with stiffening wire coiled about them. Each adjacent pair of cords is made 50 in a single piece the middle portion of which is threaded through holes 6 in a flange 7 at the upper end of one portion 8 of a clamp 9 adapted to embrace the rim 2 of the banjo head. Each cord is passed through two of 55 the holes 6 which are staggered or laterally offset one from the other, as clearly shown

in Figs. 2 and 4; the extending end portions of the cord being arranged on top of said flange 7 while the intermediate portion of the cord is looped below said flange, as at 10, 60 Fig. 3. The cords are removably held in place by a cover plate 11 having downwardly and inwardly bent flanges 12 at its lateral edges to engage the corresponding edges of the flange 7, and adapted to be 65 slipped onto said flange over the extending portions of the cords. The cover plate is made of metal or other material having sufficient resiliency to retain it in place against ordinary jars; but said plate may be slipped 70 off whenever it is desired to adjust or renew the cords.

The member 8 of the clamp has a bead or groove 13 at its upper end to bridge or fit over the edge of the clamping ring 3 of the 75 banjo head, and the cover plate 11 preferably has a lip turned up as at 120 to fit against said grooved portion 13, as shown in Figs. 1 and 2. The lower end of the member 8 of the clamp is bent inward, as at 14, 80 and has notches 15 in its edges to embrace the edges of a slot 24 in the supplemental member 19 of the clamp, there being a portion 16 beyond the notches to engage the inner face of said supplemental member, 85 whereby the inwardly bent portion 14 is retained in sliding engagement with the supplemental member.

The supplemental member 19 of the clamp has its lower end bent to engage the lower 90 edge of the rim 2 of the banjo head, as shown at 20, Fig. 1. The upper end of said supplemental member is bent outward at 21 and has notches 23 in its lateral edges to engage the edges of a slot 17 in the member 8. 95 There is a widened portion 22 beyond the notches 23 to retain the inwardly bent portion 21 in sliding engagement with the member 8. It will thus be seen that the two members of the clamp are held in spaced relation and are adapted to slide one on the other to vary the distance between the groove 13, which engages the clamping ring 3, and the bent end 20 which engages the lower edge of the rim 2. The members are assembled by first engaging the bent portion 14 with the slot 24 and then passing the part 22, which is temporarily bent upwardly at its ends to conform to the lateral extensions 18 at the upper end of the slot 17, through said 100 extensions, and finally bending the ends of the part 22 back again into horizontal po- 105 110

sition as shown. A coiled spring 27 of slightly greater diameter than the slots 17 and 24 is placed between the bent portions 14 and 21 of the members of the clamp to hold said members normally in position to yieldingly grip the rim and ring 3 of the banjo head. The spring is also slightly greater in diameter than the distance between the members 8 and 19, so that it extends into the slots 17 and 24, although it cannot pass through either of them, and is thus retained in place in the clamp.

The upper portion of the member 19 adjacent the bent end 21 and between the upper end of the slot 24 and said bent end is offset or bulged at 25 to allow clearance for the upper end of the spring. The lower end of the member 8 between the lower end of the slot 17 and the bent portion 14 is also offset or bulged in the same manner and for the same purpose, as shown at 26.

The snare may be easily attached or detached from the rim of a banjo by pressing the bent portion 14 and projecting portion 22 toward each other, which has the effect of compressing the spring and lengthening the clamp so that the groove 13 and bent part 20 at its opposite ends may clear the edges of the rim and ring of the banjo head. When the snare is in position the free ends of the snare cords 5 rest upon the head of the instrument while the cords themselves preferably extend substantially radially of the banjo head, as best shown in Fig. 5.

Having thus described my invention, what I claim as new and desire to secure by Letters Patent of the United States is:—

1. In a snare for banjos, the combination with means for fastening the same to an instrument, of a flange having perforations therein, snare cords looped through said perforations, and a cover plate removably secured over said flange for locking the cords thereto.

2. In a snare for banjos, the combination with means for fastening the same to an instrument, of a flange having perforations therein, snare cords looped through said perforations, and a cover plate having bent edges to engage the lateral edges of the flange and retain said plate on the flange for locking the cords thereto.

3. In a snare for banjos, the combination with a clamp having members adapted to grip the rim of the head of the instrument, of a bead on one clamp member to bridge the rim of the head, a flange on said member beyond the bead, and snare cords fastened to said flange.

4. In a snare for banjos, the combination with a clamp having members adapted to grip the rim of the head of the instrument, of a bead on one clamp member to bridge the rim, a flange on said member beyond the bead, said flange having perforations there-

in, snare cords looped through said perforations, and a cover plate to slidably engage said flange for locking the cords thereto.

5. In a snare for banjos, the combination with a clamp having members adapted to grip the rim of the head of the instrument, of a bead on one clamp member to bridge the rim, a flange on said member beyond the bead, said flange having perforations therein, snare cords looped through said perforations, a cover plate to slidably engage said flange for locking the cords thereto, and a lip on said plate to fit against said bead when the plate is in place on the flange.

6. The combination with a clamp having two members each having means at one end to engage one edge of the rim of a banjo and a slot in its intermediate portion, a bent portion at the other end of each member having notches to slidably engage the edges of the slot in the other member, and a coiled spring interposed between said bent end portions of the members for the purpose specified.

7. The combination with a clamp having two members, each having a slot in its intermediate portion, of means at one end of each member for engaging one edge of the rim of a banjo, means at the other end of each member to slidably engage the edges of the slot in the other member, and a coiled spring interposed between said slot-engaging means on the two members for the purpose specified.

8. The combination with a clamp having two members each having a slot in its intermediate portion, of means at one end of each member for engaging one edge of the rim of a banjo, a bent portion at the other end of each member engaging the slot of the other member, and a spring interposed between the bent end portions of the two members for the purpose specified, the diameter of the spring being greater than the width of the slots and than the space between the members, whereby said spring is retained in position.

9. The combination with a clamp having two members each having a slot in its intermediate portion, of means at one end of each member for engaging one edge of the rim of a banjo, a bent portion at the other end of each member having notches to engage the edges of the slot in the other member, one of said slots having inclined lateral extensions to permit the passage therethrough of the ends of the bent portion of the other member when said ends beyond the notches are temporarily bent to conform to said inclined extensions of the slot, and a coiled spring interposed between the bent end portions of the members for the purpose specified.

10. The combination with a clamp having two members each having a slot in its

intermediate portion, of means at one end of each member for engaging the edge of the rim of a banjo, a bent portion at the other end of each member having notches to slidingly engage the edges of the slot of the other member, a spring interposed between the bent end portions of the two mem-

bers, said spring extending into the slots, and offsets in said members between the ends of the slots and said bent end portions to 10 provide clearance for the spring.

In testimony whereof I have signed my name to this specification.

LINCOLN ISHAM.
